UNITED STATES PATENT OFFICE.

NATHAN EISEMAN, OF CHICAGO, ILLINOIS.

DESIGN FOR A CLASP.

SPECIFICATION forming part of Design No. 19,897, dated June 10, 1890.

Application filed May 5, 1890. Serial No. 350,701. Term of patent 7 years.

To all whom it may concern:

Be it known that I, NATHAN EISEMAN, a citizen of the United States, residing at Chicago, in the county of Cook and State of Illinois, have invented and produced a new and original Design for Clasps, of which the following is a specification, reference being had to the accompanying drawings, forming part thereof.

10 Figure 1 is a plan view of a clasp formed according to my design, and Fig. 2 a view in side elevation of the same.

The clasp consists of two jaw portions A A, provided with inwardly-extending ears t.

15 The object of the design is to give to the clasp a characteristic and pleasing shape which will commend itself to the public and

distinguish it from other clasps of the same general construction; and it consists in the peculiar outline of the parts A A, which are 20 shaped, as shown, to resemble or approximately resemble the sole of a human foot, the serrated engaging ends representing the toe portions and the opposite rounded ends the heel portions. 25

What I claim is—

The design for a clasp herein shown and described, the same comprising the jaws A, formed in the shape or approximately the shape of the sole of a human foot, as set forth. 30

NATHAN EISEMAN.
